PUMP

Benjamin F. Williams, Douglas, Ariz.

Application December 5, 1941, Serial No. 421,789

6 Claims. (Cl. 103—123)

My invention relates to means for impelling the flow of fluid and is particularly concerned with a pump of the positive displacement type.

It is an object of my invention to provide a generally improved pump.

Another object of my invention is to provide a pump which is relatively simple to manufacture and economical to operate.

Another object of my invention is to provide a pump in which the majority of the mass rotates.

A further object of my invention is to provide a pump in which intermittently movable valves are unnecessary.

A further object of my invention is to provide a pump in which wear in the mechanism is substantially reduced.

An additional object of my invention is to provide a pump in which the discharge is substantially continuous.

The foregoing and other objects are attained in the embodiment of the invention illustrated in the drawings, in which

Fig. 1 is a cross-section on an axial plane of the pump of my invention, portions being in elevation.

Fig. 2 is a cross-section, the plane of which is indicated by the line 2—2 of Fig. 1.

Fig. 3 is an isometric perspective view of the rotor and vane assembly, part of the baffle being shown in section on a cylindrical surface.

Figs. 4, 5, 6 and 7 are diagrams of the rotor surface developed, showing successive pumping positions of that and associated parts.

Fig. 8 is a cross-section, the plane of which is indicated by the line 8—8 of Fig. 4.

In its preferred form, the pump of my invention includes a rotor having a circular-cylindrical surface within which is provided a circumferential channel extending continuously around the rotor. The rotor also has a sinuous or irregular groove in the cylindrical surface which groove is interrupted by the channel. A stator serves as a support and enclosure for the rotor having an internal circular-cylindrical surface constituting a running fit with the rotor surface and being provided with a circumferential internal baffle which has a running fit with the channel in the rotor. In the stator is an axial channel which pierces and forms an aperture in the baffle. An abutment member having a portion adapted to slide in the axial channel, also has a portion designed to occupy a part of the groove. Inlet and outlet channels are provided in the stator to communicate with the groove on opposite sides of the abutment member and if desired, a driving

mechanism between the rotor and the abutment member can be provided so that the abutment member is made to follow the contour of the groove as the rotor is turned.

5 While the pump of my invention can readily be embodied in a number of different practical forms depending upon the particular conditions of operation which it must meet, it is successfully embodied in the exemplary form illustrated herein. In this form there is provided a stator 6 which is a housing comprised of a plurality of members, being chiefly composed of a central drum 7 and end plates 8 and 9 respectively which are secured to the drum by suitable fastening means such as studs 11. The stator so formed provides an enclosing housing and likewise is ordinarily utilized to serve as a support by the provision of feet 12 projecting from the drum 7.

10 Adapted to be disposed within the stator is a rotor, generally designated 13, which usually comprises a driving shaft 14 passing through a sealing gland 16 from the exterior to the interior of the housing and therein being borne upon bearings 17 and 18 respectively mounted within the end plates 8 and 9. Secured on the shaft 14 is a pair of relatively thick circular discs 19 and 21 suitably fastened together by through studs 22 or other comparable means and together defining a circular-cylindrical outer surface 23 which is of such a dimension as to afford a very close running fit with a corresponding circular-cylindrical inner surface 24 within the stator. The surface 23 is continuous across the face of the rotor with two exceptions one of which is a circumferential channel 28 extending entirely around the rotor.

15 As another discontinuity in the otherwise circular-cylindrical surface of the rotor, I provide a groove 29. This groove is substantially U shaped in cross-section as shown in Fig. 1, although any appropriate cross-sectional contour can be afforded, and the direction of the groove 29 is of an irregular nature so that the groove interrupts or crosses the channel 28. Preferably, the groove 29 is of a sinuous or undulatory character and can readily be made to correspond to a regular sine curve. For illustrative purposes, although it is also practically feasible, the groove 29 is shown as having various straight portions connected by relatively sharply curved junctions. Furthermore, the volumetric capacity of the pump can be increased by providing several grooves similar to the groove 29, of the same or different sizes. In any case, the important factor is that the channel 28 and the groove 29

mutually cross each other around the circumference of the rotor.

Designed to cooperate with the channel 28 in the rotor, is a baffle 31 which amounts to an interior fin or annulus preferably formed integrally with and internally extending from the interior circular-cylindrical surface of the stator, so that the channel 28 is substantially entirely filled by the baffle 31 except for the necessary running clearance. In practice, the side walls and bottom wall of the rotating channel 28 run in very close proximity to the stationary top and side walls of the baffle 31. The baffle is circularly continuous around the interior periphery of the stator except for an aperture 32 which results from the provision of an axial channel 33 cut within the stator entirely across the central drum 7 and being extended into pockets 34 and 36 respectively afforded in the side plates 8 and 9. The axial channel 33 is provided for the purpose of accommodating with a close sliding fit a platelike abutment member 41 which has a slide portion 42 and a depending portion 43, the latter of which is of such a contour and size as to fit as snugly as possible, although to afford sliding movement, into the groove 29.

The abutment member 41 is constrained to axial sliding movement in the stator and hence defines with the walls of the groove 29, with the baffle 31, and with the interior circular-cylindrical surface of the stator, chambers A and B which vary in size as the rotor is turned. Actually, two such varying chambers are provided, one on each of the opposite sides of the abutment member portion 43 so that the two chambers vary in size at the same time, one enlarging as the other one grows smaller. In addition, there is another chamber C of fixed volume not defined by the depending portion of the abutment member 43, but rather by that part of the groove 29 which is on the opposite side of the baffle 31 from the side on which the abutment member portion 43 is momentarily found.

In order to utilize the variable size chambers as pumping means, I locate in the stator 7 and preferably in the drum portion thereof, an inlet boss 51 to which is connected an inlet pipe 52 opening into an axially enlarged inlet port 53, one part of which is defined by the side wall of the abutment member 41 and another part of which is in communication at all times, being of sufficient width for that purpose, with whichever portion of the groove 29 is adjacent to one side of the abutment member 41. Likewise, there is provided an outlet boss 56 forming part of the stator and enclosing an outlet port 57 of substantially the same axial width as the inlet port 53, yet being partly defined by the opposite side of the abutment member 41 and being of sufficient width axially to communicate at all times with whatever portion of the groove 29 is adjacent the other side of the abutment member 41.

In the operation of this structure, successive positions of which are illustrated in Figs. 4 to 7 inclusive, rotation of the rotor in the direction indicated by the arrows in Figs. 2 and 4, causes the chamber B partly defined by the groove 29 and by the baffle 31 on the approaching side of the abutment member 41 continually to be decreased in size, thereby expelling the fluid content from such chamber into the outlet pipe 54 by a positive displacement. During this time, the chamber A partly defined by a successive portion of the groove 29 and by the baffle 31 on the re-

treating side of the abutment member 41, is continually increased in size thereby receiving fluid from the inlet port 53 until such time as the entire portion of the groove 29 on one side of the baffle 31 is entirely filled. This filled portion continues to rotate for part of a turn without any change in size, that is, neither decreasing nor increasing in volume, until subsequently it begins to come into registry with the outlet port 57 whereupon the abutment member 41 changes from one side of the baffle 31 to the other and commences the expulsion of the fluid by virtue of the decrease in size of the chamber portion provided by the groove 29.

This cycle repeats itself indefinitely during the rotation of the rotor and is accompanied by an axial or transverse sliding movement of the abutment member 41 in its channel and through the aperture 32. The abutment member 41 is therefore the only part of the mechanism which does not partake of a pure rotary motion so that, except for the abutment member, the pump is completely in rotary balance. The abutment member, motion, depending upon the shape of the groove 29, approximates a simple harmonic motion and by an appropriate contour of the groove the abutment member motion can be such as to produce relatively low stresses.

It is possible to drive the abutment member by contact with the walls of the groove 29, but where great precision of fit is desired and minimum wear of the fluid confining surfaces is important, I provide a driving cam 61 on the shaft 14 and cut in it a cam track 62 corresponding in contour to the contour of the groove 29. A stem 63 extends from the abutment member 41 and is provided with a cam follower 64 operating in the cam track 62. This driving mechanism appropriately moves the abutment member 41 within the groove 29 yet without frictional contact therebetween.

Sometimes, whether or not the external abutment member driving mechanism is used, it is feasible to make the groove 29 of such a contour that its sides are respectively tangent to opposite sides of the channel 28 at opposite points in the circumference of the rotor. This has an advantage in that the depending portion 43 of the abutment member 41 does not have to pass entirely through the baffle 31 but some portion of the abutment member is always supported by the baffle.

In general, therefore, the pump of my invention affords a substantially rotary pump providing for a positive displacement of the pumped fluid with the running parts substantially all in balance, and without any independently moving valves, resulting in a simple, economical and effective pumping apparatus.

I claim:

1. A pump comprising a rotor having a continuous irregular groove therein, said groove having a pair of uniformly separated side walls, a stator forming a closure for said groove, a baffle on said stator interrupting both of the side walls of said groove and forming a complete dividing wall across said groove at spaced points along said groove, an abutment member adapted to occupy part of said groove for substantially the full depth and width of said groove and to pierce said baffle, a fluid inlet to said groove adjacent one side of said abutment member, a fluid outlet from said groove adjacent the other side of said abutment member, said inlet and outlet being adapted to communicate with the groove on opposite

sides of the baffle during rotation of the rotor, and means for rotating said rotor.

2. A pump comprising a cylindrical rotor having a continuous sinuous groove therein, said groove having a pair of uniformly spaced side walls, a stator forming a closure for said groove, a baffle on said stator interrupting both of said side walls of said groove and forming a complete dividing wall across said groove at spaced points along said groove, said baffle having an axial aperture therein, an abutment member adapted to occupy part of said groove for substantially the full depth and width of said groove and to slide through said aperture, a fluid inlet to said groove in said stator on one side of said abutment member, and a fluid outlet from said groove in said stator on the other side of said abutment member, said inlet and outlet being adapted to communicate with the groove on opposite sides of the baffle during rotation of the rotor.

3. A pump comprising a cylindrical rotor having a continuous sinuous groove in the cylindrical surface thereof, said groove having a pair of uniformly spaced side walls, a stator having a running fit with said surface and constituting a closure for said groove, a baffle on said stator interrupting both of said side walls and forming a complete dividing wall across said groove at spaced points along said groove, said baffle having an axial aperture therein, an abutment member adapted to occupy part of said groove for substantially the full depth and width of said groove and to slide through said aperture and fluid conducting means communicating with said groove on opposite sides of said abutment member during rotation of the rotor.

4. A pump comprising a rotor having a cylindrical surface, said rotor having a continuous sinuous groove provided with a pair of side walls and a circumferential channel intersecting both of the side walls of said groove, a stator enclosing said rotor and therefore said groove, a baffle on said stator extending into said channel and interrupting both of said side walls and forming a complete dividing wall across the groove at spaced points along the groove, said baffle hav-

ing an axial aperture therein, an abutment member adapted to slide in said aperture and occupy a part of said groove for substantially the full depth and width of said groove and fluid conducting means opening into said groove on opposite sides of said abutment member during rotation of the rotor.

5. A pump comprising a rotor having a cylindrical surface, said rotor having a continuous sinuous groove provided with a pair of side walls and a circumferential channel intersecting both of said side walls, a stator enclosing said rotor and therefore said groove, a baffle on said stator extending into said channel and interrupting both of said side walls and forming a complete dividing wall across the groove at spaced points along the groove, said stator having an axial channel piercing said baffle to provide an aperture therethrough, an abutment member adapted to slide in said axial channel and through said aperture, said abutment member having a portion occupying part of said groove for substantially the full depth and width of said groove, and fluid conducting means opening into said groove on opposite sides of said abutment member during rotation of the rotor.

6. A pump comprising a rotor having a cylindrical surface with a continuous sinuous groove therein provided with a pair of side walls, a stator enclosing said rotor and having an axial channel therein, a baffle on said stator extending into said channel and interrupting said side walls and forming a complete dividing wall across the groove at spaced points along the groove, an abutment member slideable in said axial channel and having a portion occupying part of said groove for substantially the full depth and width of said groove and means independent of the camming action of said side walls on said abutment member for sliding said abutment member on rotation of said rotor to follow the configuration of said groove and fluid conducting means communicating with said groove on opposite sides of the said abutment during rotation of the rotor.

BENJAMIN F. WILLIAMS,
